SPECTROGRAPHIC PIN STAND

Edward J. Dunn, West Mifflin, Pa., assignor to
Carnegie-Illinois Steel Corporation, a corpora-
tion of New Jersey

Application February 12, 1947, Serial No. 727,988

10 Claims. (Cl. 315—76)

1:

This invention relates to an improved stand for holding specimens for spectrographic analysis.

Among the objects of the invention is the provision of an improved spectrographic specimen stand, hereafter called a spectrographic pin stand, which is adapted to be used for holding therein opposed pins or one flat sample and an opposed pin, the change from the first type of specimen to the second, or vice versa, being quickly and easily accomplished.

A further object of the invention lies in the provision of such spectrographic pin stand wherein the specimens consisting of the opposed pins or the opposed flat sample and pin are easily and accurately located during loading.

Another object of the invention lies in the provision of safety mechanism in combination with the high tension current supply for such spectrographic pin stand, whereby flow of such current to the stand is prevented unless the pin carrying slide is fully inserted into exciting position.

These and further objects of the invention will be more readily apparent in the following description of a preferred embodiment of the invention.

Spectrographic analysis of materials is being employed more and more widely both in laboratory and production work since improvements of the spectrographic equipment have made it possible to determine quantitatively certain elements with much greater speed than wet chemical methods and with comparable accuracy. This increased speed of analysis materially shortens the time necessary for preparing certain metals such as copper, aluminum, steel, iron, etc. and their alloys.

In general, there are two forms of specimens which are employed in spectrographic analysis, the elongated electrode or pin and the flat plate. The pin may be made by casting the metal desired to be analyzed in pin form. The pin may, however, consist of a carbon electrode having a cavity in its end, the metal to be analyzed being placed in such cavity in powdered form. The electrodes are usually placed in a pin stand on an optical bench of a spectrograph, the specimen pin being placed on the bottom in a vertical position and a plain carbon electrode being placed in opposed relationship with a standard gap between them. The application of a standard voltage to the electrodes forms an arc between them, the spectrum of which is analyzed by the spectrograph.

Heretofore, flat samples of metals to be analyzed have been held in a stand called the Petrey stand, which is of quite different design from that of the pin holders previously used. In the

2:

Petrey stand the flat sample is held in horizontal position above a vertical carbon electrode placed at a standard distance from the underside thereof, the arc then being created between the upper end of the electrode and the lower surface of the flat sample. Formerly, when it was necessary to change from the analysis of pins to flat samples and vice versa it was necessary completely to remove one type of specimen holder from the optical bench and replace it with another. Such operation required a considerable amount of time. The pin holder of the present invention makes possible the change from one type of sample to another with only the removal of a slideable specimen or pin holder from the stand and its replacement by another specimen holding slide, an operation which takes but a few seconds. Excitation of the samples is prevented by a novel safety mechanism of the invention until the specimen carrying slide is inserted in the holder and lies in its operative position.

The invention will be more readily understood by reference to the accompanying drawings in which:

25 Figure 1 is a view in elevation of the pin stand assembly with a holder for two opposed pin samples mounted therein;

Figure 2 is a view in plan of the apparatus shown in Figure 1;

30 Figure 3 is a view in vertical section through the pin stand holder with the pin holding slide removed, the section being taken along the line III—III of Figure 2;

Figure 4 is an enlarged view in side elevation of the pin holding slide shown in Figures 1 and 2;

35 Figure 5 is a view in horizontal cross section through the pin holding slide of Figure 4, the view being taken along the line V—V of Figure 4;

Figure 6 is a view in side elevation of a pin positioning jig employed in the loading of the pin holding slide shown in Figures 1, 2, 4, and 5;

Figure 7 is a view in end elevation of the jig shown in Figure 6 with the pin holding slide shown in Figures 4 and 5 mounted therein;

45 Figure 8 is a view in side elevation of the specimen holder with a modified pin holding slide placed therein for holding the bottom pin in the analysis of flat samples;

Figure 9 is a view in side elevation of the bottom pin holding slide shown in Figure 8;

Figure 10 is a view in plan of the pin holding slide shown in Figure 9;

Figure 11 is a view in side elevation of a jig for positioning the pin during the loading of the slide shown in Figures 9 and 10;

Figure 12 is a view in end elevation of the jig shown in Figure 11 with the pin holding slide shown in Figures 9 and 10 mounted therein; and

Figure 13 is a diagrammatic view of the current supply and safety circuits for spectrographic pin stand.

The pin stand of the invention, indicated generally by the character 4 in Figure 1, is adapted for mounting upon the optical bench 2 of a spectrograph. The pin stand is provided with base 6 having longitudinal grooves therein interfitting with the tracks of the bench. Base 6 is provided with the central vertically projecting boss 8, and with bosses 10 and 12 at the right and left hand ends thereof, as shown in Figure 1, respectively. The supporting frame for the specimen carrying slide is generally indicated by the reference character 14. Frame 14 is supported from the base 6 by means of column 16, made of suitable insulating material such as a phenolic resin, adjustably mounted, as shown, in boss 8. Frame 14 consists of a horizontal bottom plate 18 made of metal having a longitudinal slot 20 therein for the reception of the lower edge of the pin holding slide, as shown in Figure 3. The frame is further provided with a metal top plate 26 parallel to plate 18, having a slot 28 therein extending throughout a major portion of the length of the plate. Plates 18 and 26 are connected by vertical insulating blocks, those at the left hand side in Figure 1 at the front and back of the apparatus being designated 22 and 24, respectively. The inner faces of the blocks are placed in alignment with the corresponding edges of slots 20 and 28 to provide a slide receiving channel therebetween. Block 22 is provided with horizontal slot 25 to provide clearance for the bottom pin retaining spring mounted on the pin holding slide, subsequently to be described.

The frame is completed by an insulating block 27 shown at the right in Figure 1, having a vertical slot in its inner face lining up with slots 26 and 28. Top plate 26 of the frame is provided with semi-circular recess 30 in the forward portion thereof adjacent the slide receiving slot 28 and with a longitudinal opening 32 communicating with recess 30, as shown in Figure 2. Recess 30 and slot 32 allow room for the arc and for observation thereof from the spectrographic camera, respectively.

The pin carrying slide 34, as shown in Figure 4, is inserted in the guideway defined by the slots 28 and 20 in the top and bottom plates, respectively, of the frame, the space between the insulators 22, 24 and the vertical slot in block 27. The body portion of such slide has a vertically extending handle 38 made of an insulating material such as a phenolic resin, secured to the left hand edge thereof as shown. The top electrode or pin 40 and the bottom electrode or pin 42 are positioned in opposed coaxial relationship with a predetermined standard gap between.

The slide is composed of top and bottom metal electrode carrying portions secured together to form a unitary structure in which the two pin carrying portions are insulated from each other. The top metal body portion 44, which is of a generally inverted U-shape as shown in Figure 4, is provided centrally thereof with a vertical forward facing V groove 46 which receives the pin 40. The pin is held in the groove by a horizontal bent leaf spring 48. The bottom metal portion 50 of the slide is likewise provided with a vertical forward facing V groove 52 for the reception of bottom pin 42, the pin being retained in the

groove by the bent leaf spring 54. The two metal portions of the slide are connected at their forward ends by the insulating member 56, which may be made of synthetic resin. The upper and lower ends of member 56 extend into vertical slots in members 44 and 50, respectively, and are secured therein by bolts as shown. The rear ends of members 44 and 50 are connected together by being bolted to the integral handle 38 as shown in Figure 4.

To insure the correct initial setting of the top and bottom pins with the standard gap between their opposed ends there is provided the jig 86 shown in Figures 6 and 7. This jig is composed of a flat plate 88 having generally the same length and height as the body of the slide. Plate 88 is provided with top and bottom flange plates 94 and 90, respectively, extending at right angles to plate 88 and secured thereto as by screws. Plate 88 is further provided on one edge with a flange plate 96. The distance between the inner faces of plates 96 and 94 is made the same as the height of the slide so that it may be snugly received therebetween as shown in Figure 7. The slide is retained in such position by means of yieldable friction plugs 92 recessed into plate 90. On its forward face plate 88 carries a gauging means for determining the gap between pins, including a T-shaped member having oppositely extending feet 100 and the horizontal forwardly projecting gauge plate 98. Feet 100 fit within a vertical slot provided in the face of plate 88 and are held therein by screws 104. Slots 102 in feet 100 through which screws 104 extend allow the vertical adjustment of gauge plate 98.

When slide 34 is inserted in the jig 86, as shown in Figure 7, pins 40 and 42 may be inserted in the grooves therein and thrust into engagement with gauge plate 98, the thickness of which is equal to the standard gap employed between the electrodes in spectrographic analysis.

The supply of exciting voltage to pins 40 and 42 is effected in the following manner. A conductor, not shown, connected to one side of a suitable current source, extends through an insulator 60 carried by boss 12 and is connected to a binding post 64 from which connection to the bottom metal plate 18 of the pin stand frame is made by a jumper 68. A conductor connected to the other side of the current source is brought up through an insulator 58 carried by boss 10 to a binding post 62, from which connection is made to the upper plate 26 of the holder frame by a jumper 66. The upper metal portion 44 of the pin carrying slide has spring pressed contacts 76 adapted to engage plate 26, recessed into the rear face thereof as shown in Figure 4. When the slide is inserted in the frame the outer ends of the contacts extend within the V groove 72 in plate 26, shown in Figure 3. Contact between the lower metal portion 50 of the pin carrying slide and plate 18 is effected by similar contacts 74, the ends of which extend within V groove 70 in plate 18 when the slide is inserted in the channel in the holder.

In order to prevent connection of the holder to the high voltage source until the pin carrying slide is inserted in the frame and is in exciting position, I provide a safety mechanism shown in Figures 1 and 2 and diagrammatically indicated in the circuit shown in Figure 13. Such mechanism consists of a microswitch 78 which makes and breaks a control circuit having leads 80 and 80'. The construction of the switch, which is conventional, is such that its contacts

are normally open but are closed by engagement of the slide with switch-actuating arm 84. A headed plunger 82 extends through a hole in the block 27, as shown, so that when the pin carrying slide 36 is withdrawn, the inner end of plunger 82 may enter the slide receiving slot as arm 84 is moved by its restoring spring to break the circuit. When the slide enters the slot, however, the forward end thereof engages the inner end of plunger 82 thrusting it outwardly, thereby actuating arm 84 and closing the circuit.

The manner in which the safety mechanism is connected to the current supply circuit will be more clearly understood from Figure 13. Conductor 68, leading to the holding means for pin 42, is connected directly to one side of the source of high voltage, not shown. A conductor 146 connected to the other side of the source, however, is controlled by a manual switch 160 and the contacts 150 of a relay 148 controlled by the microswitch. The control circuit is provided with a source of direct current 154, the microswitch being connected in series with such source and with the coil 152 of relay 148 by conductors 80, 80' and 158. The relay opens its contacts 150 when its coil is deenergized, thus breaking the high voltage circuit to the pin holder. When microswitch 78 is closed coil 152 is energized and contacts 150 in the supply circuit are closed, thereby putting the supply circuit in readiness for arcing of the pins by the closing of the switch 160.

When the specimen to be analyzed is a flat plate, the pin stand arrangement shown in Figures 8, 9, and 10 is employed. Such stand employs the same holder as that used in the first embodiment; and the parts of holder and frame are designated by the same reference characters. For arcing specimens of this type the slide 36 is replaced by the slide 106, shown in Figures 9 and 10, for holding the bottom plain carbon pin 118.

Slide 106 consists of a body 108, the insulating handle 110 being secured to the outer edge thereof, as shown in Figure 9. The body is made up of the bottom metal portion 112 having the vertical forward facing V groove 114 therein for the reception of the lower portion of pin 118, the pin being secured in such groove by the bent leaf spring 116. The top portion of the slide is made up of the metal member 120, such part being secured to the lower member 112 at its forward end through the medium of insulating member 122, the ends of which fit in slots in members 120 and 112, respectively, and by handle 110 to which it is secured by bolts, as shown. Upper member 120 is provided with a forward facing recess 124 of substantial size as shown in Figure 10 to give room for the arc, such recess communicating with an opening 126 extending through the rear face of member 120. Connection of member 112 to the bottom plate 18 of the holder is effected by contacts 128 received in groove 70, the top member 120 being similarly connected to top metal plate 26 by contacts 130 received in groove 72.

When the pin holding slide shown in Figures 9 and 10 is inserted in the holder as shown in Figure 8 the flat metal specimen, not shown, is laid above the upper end of pin 118 and across the top frame member 26 and the top slide member 120, the upper surfaces of which lie in the same plane. The holder thereupon being supplied with exciting current, an arc is struck between the upper end of the pin and the bottom surface of the flat specimen.

Correct positioning of pin 118 is insured by the use of jig 132 shown in Figures 11 and 12. Such jig is composed of a main body plate 134 having upper and lower flange plates 136 and 138 secured thereto. The jig is also provided with a flange 140 on one edge. Friction plugs 142 recessed in the bottom plate 138 removably retain slide 106 in the jig in the position shown in Figure 12. The upper flange plate 136 is provided on its lower edge with a gauge plate 144 so positioned that it will be engaged by the upper end of pin 118. The thickness of the gauge plate is such that when the slide 106 is inserted in the holder there will be a standard gap between the upper end of pin 118 and the bottom surface of the flat sample lying on members 26 and 120.

A further safety feature provided in the device is an auxiliary gap connected in parallel with the electrode carrying members on the slide. Such auxiliary gap in the first embodiment consists of opposed members 162 affixed to parts 44 and 50, respectively, of the slide, and in the second embodiment consists of opposed members 162' affixed to parts 112 and 120, respectively, of the slide. The distance between the adjacent ends of members 162 and 162' is made somewhat greater than the standard gap between electrodes or electrode and flat sample so that the arc occurs at the samples when they are in place and the holder energized. If the electrodes or electrode and flat sample should not be in position when the holder is energized, however, the arc occurs at the auxiliary gap, preventing the possibility of breakdown of the various insulating parts of the holder and slide.

Although I have illustrated and described a preferred embodiment of the improved spectrographic pin stand of my invention, the latter is capable of considerable variation within the teaching of the invention. I, therefore, desire to claim as new the following:

1. A spectrographic pin stand comprising a holder adapted to be mounted on an optical bench, said holder comprising a vertical frame having a vertical guideway extending substantially therethrough, the frame being made up of a lower horizontal electrically conducting member, an upper horizontal electrically conducting member parallel thereto, and laterally and longitudinally spaced vertical electrically insulating members connecting the upper and lower conducting members, the lateral spacing of the vertical members being sufficient to form the aforementioned guideway, an electrode carrying slide adapted to be snugly received in the guideway of the frame, means on the slide to mount an electrode in position for excitation and means on the slide comprising a resiliently mounted contact making electrical connection between one of the electrically conducting members of the frame and the mounting means for the electrode.

2. A spectrographic pin stand comprising a holder adapted to be mounted on an optical bench, said holder comprising a vertical frame, the frame being made up of a lower horizontal electrically conducting member, an upper horizontal electrically conducting member parallel thereto, and laterally and longitudinally spaced vertical electrically insulating members connecting the upper and lower members, the lateral spacing of the vertical members being such as to form a guideway of appreciable width therebetween, the longitudinal spacing of the vertical members being substantial so as to form an opening of appreciable size transversely through the

frame, an electrode carrying slide adapted to be snugly received in the guideway of the frame, means on the slide to mount an electrode in position in front of the transverse opening through the frame thereon for excitation, a source of exciting current, means connecting the two conducting members to opposite polarities of said source, and means on the slide comprising a resiliently mounted contact making electrical connection between one of the electrically conducting members of the frame and the mounting means for the electrode.

3. A spectrographic pin stand comprising a holder adapted to be mounted on an optical bench, said holder comprising a vertical frame having a longitudinal guideway therein, the frame being made up of a lower horizontal electrically conducting member, an upper horizontal electrically conducting member parallel thereto, and laterally and longitudinally spaced vertical electrically insulating members connecting the upper and lower members, the longitudinal spacing of the vertical members being substantial so as to form an opening of appreciable size transversely through the frame, the lateral spacing of the vertical members being such as to form the above-mentioned guideway therebetween, an electrode carrying slide adapted to be snugly received in the guideway of the frame, means on the slide to mount an electrode in position thereon for excitation, a source of exciting current, a circuit for connecting the two conducting members to opposite polarities of said source, means comprising a resiliently mounted contact making electrical connections between one of the electrically conducting members of the frame and the mounting means for the electrode, and means to open the exciting circuit when the slide is withdrawn appreciably from the exciting position in the guideway and to restore such circuit to a condition to be closed when the slide is advanced into exciting position in the guideway.

4. A spectrographic pin stand comprising a holder adapted to be mounted on an optical bench, said holder comprising a vertical frame, the frame being made up of a lower horizontal electrically conducting member, an upper horizontal electrically conducting member parallel thereto, and laterally and longitudinally spaced vertical electrically insulating members connecting the upper and lower members, the lateral spacing of the vertical members being such as to form a guideway of appreciable width therebetween, the longitudinal spacing of the vertical members being substantial so as to form an opening of appreciable size transversely through the frame, an electrode carrying slide adapted to be snugly received in the guideway of the frame, means on the slide to mount an electrode in position thereon for excitation, a source of exciting current, a circuit for connecting the two conducting members to opposite polarities of said source, means on the slide comprising a resiliently mounted contact making electrical connection between one of the electrically conducting members of the frame and the mounting means for the electrode, and means to open the exciting circuit when the slide is withdrawn appreciably from the exciting position in the guideway and to restore such circuit to a condition to be closed when the slide is advanced into exciting position in the guideway, said last named means comprising a control circuit, a switch in the control circuit, a relay having a coil in said circuit and contacts, closed when the coil is energized and opened

when the coil is deenergized, in the first-mentioned circuit, means opening and closing the switch including a member operatively connected thereto and projecting into the guideway in position to be contacted by the slide when it is in exciting position to close the switch.

5. A spectrographic pin stand comprising a holder adapted to be mounted on an optical bench, said holder comprising a frame having a guideway therein, spaced electrically conducting members insulated from each other exposed in said guideway, a source of exciting current, means connecting the two conducting members to opposite polarities of said source, a removable electrode carrying slide adapted to be received in the guideway of the frame, two opposed mounting means on the slide electrically insulated from each other to mount opposed electrodes in position for excitation, means on the slide making electrical connection between one of the electrically conducting members of the frame and the mounting means for one of the electrodes, and means on the slide making electrical connection between the other of the electrically conducting members of the frame and the mounting means for the other of the electrodes.

6. A spectrographic pin stand comprising a holder adapted to be mounted on an optical bench, said holder comprising a vertical frame having a vertical guideway extending substantially therethrough, the frame being made up of a lower horizontal electrically conducting member, an upper horizontal electrically conducting member parallel thereto, and laterally and longitudinally spaced vertical electrically insulating members connecting the upper and lower members, the lateral spacing of the vertical members being sufficient to form the aforementioned guideway, an electrode carrying slide adapted to be snugly received in the guideway of the frame, two opposed mounting means on the slide electrically insulated from each other to mount a pair of opposed electrodes in position for excitation, means comprising a resiliently mounted contact making electrical connection between one of the electrically conducting members of the frame and the mounting means for one of the electrodes, and means comprising a resiliently mounted contact making electrical connection between the other of the electrically conducting members of the frame and the mounting means for the other of the pin samples.

7. A spectrographic pin stand comprising a holder adapted to be mounted on an optical bench, said holder comprising a vertical frame, the frame being made up of a lower horizontal electrically conducting member, an upper horizontal electrically conducting member parallel thereto, and laterally and longitudinally spaced vertical electrically insulating members connecting the upper and lower members, the lateral spacing of the vertical members being such as to form a guideway of appreciable width therebetween, the longitudinal spacing of the vertical members being substantial so as to form an opening of appreciable size transversely through the frame, an electrode carrying slide adapted to be snugly received in the guideway of the frame, said slide comprising spaced upper and lower members of electrically conducting material, insulating members connecting the upper and lower members, means on the slide to mount a pair of opposed electrodes in exciting position in front of the transverse opening through the frame, said means comprising an electrode holding means on

the upper member of the slide and an opposed electrode holding means on the lower member of the slide, a source of exciting current, means connecting the two conducting members of the frame to opposite polarities of said source, and means making electrical connection between the upper conducting members of the frame and the slide and between the lower conducting members of the frame and the slide.

8. A spectrographic pin stand comprising a holder adapted to be mounted on an optical bench, said holder comprising a vertical frame, the frame being made up of a lower horizontal electrically conducting member, an upper horizontal electrically conducting member parallel thereto, and laterally and longitudinally spaced vertical electrically insulating members connecting the upper and lower members, the lateral spacing of the vertical members being such as to form a guideway of appreciable width therebetween, the longitudinal spacing of the vertical members being substantial so as to form an opening of appreciable size transversely through the frame, an electrode carrying slide adapted to be snugly received in the guideway of the frame, said slide comprising spaced upper and lower members of electrically conducting material, insulating members connecting the upper and lower members, means on the slide to mount a pair of opposed electrodes in exciting position in front of the transverse opening through the frame, said means comprising an electrode holding means on the upper member of the slide and an opposed electrode holding means on the lower member of the slide, a source of exciting current, means connecting the two conducting members of the frame to opposite polarities of said source, and means to open the exciting circuit when the slide is withdrawn appreciably from the exciting position in the guideway and to restore such circuit to a condition to be closed when the slide is advanced into exciting position in the guideway.

9. A spectrographic pin stand for flat samples comprising a holder adapted to be mounted on an optical bench, said holder comprising a vertical frame having a guideway therein, upper and lower spaced electrically conducting members insulated from each other exposed in said guideway, the upper conducting member forming the top of the frame, a source of exciting current, means connecting the two conducting members to opposite polarities of said source, a removable electrode carrying slide adapted to be received in the guideway of the frame, means on the lower portion of the slide to mount an electrode in upright position for excitation, and means making electrical connection between the lower electrically conducting member of the frame and the

mounting means for the electrode, the upper conducting member of the frame having a vertical opening therethrough in line with the electrode when the slide is inserted into the guideway in exciting position, whereby an arc may be struck between the electrode and the bottom surface of a flat sample lying on the upper conducting member of the frame over the vertical opening therethrough.

10. A spectrographic pin stand for flat samples comprising a holder adapted to be mounted on an optical bench, said holder comprising a vertical frame having a vertical guideway extending substantially therethrough, the frame being made up of a lower horizontal electrically conducting member, an upper horizontal electrically conducting member parallel thereto, and laterally and longitudinally spaced vertical electrically insulating members connecting the upper and lower members, the lateral spacing of the vertical members being sufficient to form the aforementioned guideway, the longitudinal spacing of the vertical members being such as to form a transverse opening of substantial size through the frame, an electrode carrying slide adapted to be snugly received in the guideway of the frame, means on the lower portion of the slide to mount an electrode in upright position in front of the transverse opening for excitation, means comprising a resiliently mounted contact making electrical connection between the lower electrically conducting member of the frame and the mounting means on the slide for the electrode, the upper conducting member of the frame having a vertical opening therethrough in line with the electrode when the slide is inserted into the guideway in exciting position, whereby an arc may be struck between the electrode and the bottom surface of a flat sample lying on the upper conducting member of the frame over the vertical opening therethrough, and means to open the exciting circuit when the slide is withdrawn appreciably from the exciting position in the guideway and to restore such circuit to a condition to be closed when the slide is advanced into exciting position in the guideway.
